UNITED STATES PATENT OFFICE.

WILLIAM H. MCGANN, OF MINNEAPOLIS, MINNESOTA.

CAR-DOOR.

1,343,925.

Specification of Letters Patent. Patented June 22, 1920.

Application filed September 2, 1919. Serial No. 320,988.

To all whom it may concern:

Be it known that I, WILLIAM H. MCGANN, a citizen of the United States, residing at Minneapolis, in the county of Hennepin and State of Minnesota, have invented certain new and useful Improvements in Car-Doors; and I do hereby declare the following to be a full, clear, and exact description of the invention, such as will enable others skilled in the art to which it appertains to make and use the same.

My invention relates to car doors and has for its object to provide an improved lock and operating mechanism therefor. Generally stated, the invention consists of the novel devices and combinations of devices hereinafter described and defined in the claims.

Particularly, the invention provides a simple and efficient means, first for positively moving the side door of a freight car; and second, for locking and sealing the same either in closed or in more or less open positions. For the shipment of fruit, grain and various other commodities, ventilation within the car is of the utmost importance, and for this reason, inspectors, at certain points along the line, inspect the cars and determine whether or not the side doors must be opened slightly to give the desired ventilation. My invention provides a very simple and highly efficient device which meets all of the conditions incident to the above noted operation and permits the car door to be locked and sealed in various different more or less open positions, as well as in closed position. The invention also involves certain other features as will hereinafter appear.

The invention is illustrated in the accompanying drawings wherein like characters indicate like parts throughout the several views. Referring to the drawings:

Figure 1 is a side elevation showing a freight car body with some parts broken away, illustrating my invention applied to one of the sliding side doors thereof;

Fig. 2 is an enlarged side elevation of the lock mechanism and coöperating door moving devices; and

Fig. 3 is a vertical section taken on the line 3—3 of Fig. 2.

Of the customary parts of the car, the numeral 4 indicates the car body, and the numeral 5 one of its side doors, which latter is provided at its upper edge with wheel-

equipped hanger brackets 6 arranged to travel on an overhead rail 7 in the customary way. The numeral 8 indicates the lower door hanger brackets, the numeral 9 the door stop, and the numeral 10 the usual hasp fastening that is adapted to be sealed in the customary way, if desired.

In the application of my invention, I provide a rack bar 11 which is secured to the outer surface of the side of the car body and extends horizontally thereof along a line considerably above the lower edge of the door 5. This rack 11 is shown as provided with threaded bolts 12 which, at the inner side of the car body, are equipped with nuts 13 that securely clamp the said rack in position. For an important purpose which will presently be noted, this rack is made dove-tailed in cross section. 75

Meshing with the rack 11 is a pinion 14 that works within a housing 15 rigidly secured to the door 5 near one edge thereof. This housing 15 is preferably clearly set into the door, and the door, at its inner side, is formed with a channel into which is set, and rigidly secured, an internally dove-tailed metal retaining channel 16 rigidly secured by screws, bolts, rivets, or otherwise, to the case hinge of the housing 15 and to the door stop. Here it may be noted that the interlocking sliding engagement between the dove-tailed rack and the channel 16 positively prevents the door from being pried laterally away from the car body so as to thereby disengage the lower edge from the door from one or both of the lower hanger brackets 8. Hitherto, car doors of this kind have been pried open and goods removed from the car without breaking the car seal. 95 This operation is prevented by the device just described.

The pinion 14 is rigidly secured to a short upright stem 17 which, at its lower end, and below the case 15, is provided with a head 18 having diametrical perforations 19.

Pivoted at its lower end at 20, the ears 21 on the lower flange 15^a, of the housing 15, is a lock piece 22 which, at its free upper end, is provided with a loosely projecting lock pin 23 that is adapted to engage with the aligned perforations 19 of the head 18. The lock pin 23 has an elongated seal passage 24 that intersects the perforation 19 upon which lock pin 23 is inserted. A horizontal car seal 25 is adapted to be applied to the seal passage 24 of the lock pin 23 and the

aligned perforation 19 to thereby lock and seal the lock piece or lever 22 in its operative position shown by full lines in Fig. 3. Obviously, when the lock pin 23 is secured in one of the perforations 19, the stem 17 and, hence the pinion 24, will be locked against rotation, thereby locking the pinion to the rack and securing the car door against sliding movement. Obviously, also, the pin 23 can be engaged with the perforation 19 in either the closed position of the door or, substantially, in a more or less open position of the door. This device, therefore, affords positive means for locking and sealing the car with the door in various different adjustments. The car door, therefore, can be opened far enough to permit good ventilation but not far enough to permit a person to enter the car and the car door can be locked and sealed in such position.

The numeral 26 indicates a spring fork secured to the depending flange 15^a, and engageable with the intermediate portion of the lock lever 22 to yieldingly hold the same in an upturned operative position. The prongs of this fork spring 26 are shown as provided with seal passages 27 to which a car seal may also be inserted if desired.

Frequently, a car door will stick so that it is difficult to start the movement thereof from its closed to its open position, or, conversely, and many car doors have been broken or damaged by the use of a crow bar or sledge to effect a sliding movement thereof. With this device, a bar can be inserted in one of the perforations 19 of the stem head 18 and great force can be thus exerted through the pinion and rack to positively move the door without in any way damaging the door. The device designed may be applied to ordinary car door or may be incorporated in new car doors.

What I claim is:

1. The combination with a car body having a sliding door, of a rack secured to said car body, a pinion journaled on the car door and meshing with said rack, said pinion having a stem with a perforated head, a lock piece mounted on the car door and engageable with the perforated head of said stem to

lock said pinion against rotation in different adjustments of the door.

2. The combination with a car body having a sliding door, of a bar secured to said car body, and a retaining channel on said door, said channel engaging said bar with a sliding but interlocking engagement and holding said door against lateral separation from the car body.

3. The combination with a car body having a sliding door, of a rack secured to said car body, a retaining channel secured to said door and having an interlocking sliding engagement with said rack, a pinion journaled on said door and meshing with said rack, and a lock lever carried by said door and operative to lock said pinion against rotation in different adjustments of the door.

4. The combination with a car body having a sliding door, of a rack secured to said car body, a retaining channel secured to said door and having an interlocking sliding engagement with said rack, a pinion journaled on said door and meshing with said rack, and a lock lever carried by said door and operative to lock said pinion against rotation in different adjustments of the door, said lock lever having a lock element with a seal passage therein whereby it may be locked in an operative position by an applied seal.

5. The combination with a car body having a sliding door, of a rack secured to said car body, a pinion journaled on said door and meshing with said rack, said pinion having a stem with intersecting diametrical perforations therein, and a lock lever pivoted to said door and having a projecting lock pin insertible through an aligned perforation of said pinion stem, and said lock pin having a seal passage through which and the perforation of said stem that is aligned therewith, a seal may be applied to secure said lock lever in an operative position.

In testimony whereof I affix my signature in presence of two witnesses.

WILLIAM H. McGANN.
